UNITED STATES PATENT OFFICE.

JAMES B. KNICKERBOCKER, OF INDIANAPOLIS, INDIANA.

PRESSURE-REGULATOR.

SPECIFICATION forming part of Letters Patent No. 468,007, dated February 2, 1892.

Application filed December 26, 1890. Serial No. 375,782. (No model.)

To all whom it may concern:

Be it known that I, JAMES B. KNICKERBOCKER, of Indianapolis, county of Marion, and State of Indiana, have invented certain 5 new and useful Improvements in Pressure-Regulators; and I do hereby declare that the following is a full, clear, and exact description thereof, reference being had to the accompanying drawings, in which like figures refer to 10 like parts.

My invention relates to the construction of devices for regulating the pressure in gas-mains and service-pipes, and will be understood from the following description.

15 In the drawings, Figure 1 is an elevation of my device. Fig. 2 is a section on the line $x x$, Fig. 1. Fig. 3 is an enlarged detail view of the reducing-valve. Fig. 4 is an enlarged detail view of the escape-valve.

20 In detail, 1 is a casing centrally divided, and 2 a diaphragm secured therein, having a metal backing-plate 3 upon the top.

4 is the diaphragm-stem, centrally threaded, upon which works a nut 5, confining the dia- 25 phragm and its backing-plate between it and a flange 6, formed on the diaphragm-stem, the upper end of this rod screwing into a head 8, providing bearings for the pivot-pin 9, by which the lever 10 is connected to the dia- 30 phragm-rod. This lever is pivoted at 11 to a projection 12, connected to the casing, and has an adjustable counter-weight 13 on its op- posite end.

14 is a cup resting on a shoulder on the 35 diaphragm-stem and clamped between such shoulder and the head 8, which is threaded on the end of the stem. At the lower end of the diaphragm-stem is a regulating-valve 15, whose seat is at 34, its stem 17 being provided 40 with short grooves to admit the passage of the gas upward from the chamber 18 below, to which a pipe leads from the well, and 19 is an opening above the regulating-valve 15, where the service-pipe is connected.

45 20 is a small outlet-pipe, also connected above the valve 15, leading through the union 21 to the chamber 22, in which is seated the escape-valve 23, its stem having a slot 24 at its upper end and engaging with the end 25 50 of the lever 26, which is centrally pivoted at 27 to a projection 28 of the casing, the oppo-

site end 29 of this lever forming a hook which is adapted to engage behind the wall of the cup 14 at the proper time.

30 is an outlet-pipe to the open air. 55 The valve-stem 17 is screwed into the dia- phragm-stem and at their junction the latter is rounded at 32 to form a cut-off valve whose seat is at 33 below. The grooves in the valve- stem 17 are formed opposite each other, the alternate ones being of unequal length and neither of these extends down to the button of the valve 15, and the object of stopping these short of the valve and of making them of different lengths is to prevent the jumping 65 of the valve when the consumption is sud- denly increased. When the gas is first ad- mitted through the valve, it passes through the longer grooves, and when another fire is started and more gas is required the valve 70 will then drop until the gas is also admitted through the shorter grooves, in this case regu- lating the pressure upon the diaphragm and the amount of gas consumed, preventing any jumping or pulsating movement of the valve. 75 If these grooves were of the same length, the gas would enter through all simultaneously, and upon an increase of pressure there would be nothing to prevent the pulsating move- ment of the valve. Again, if all the grooves 80 were of one length, when the valve was opened the gas would enter through all the grooves; but the opening in each would be so small that it would hardly be seen, and if another fire was started the valve would drop corre- 85 spondingly, opening all the grooves or ports a little farther, but yet so that it might not make any perceptible difference in the move- ment of the valve; but by making the grooves of different lengths, so as to open first one and 90 then another set of ports, it gives the valve a sensible movement and keeps the machine at all times in operative condition and tends to prevent freezing or sticking of the parts.

The lever, with the weight, is so pivoted that 95 the rising of the weight operates to close the reducing-valve and its fall tends to open that valve. The weight, however, always acts against the pressure beneath the diaphragm, and it is intended that the weight shall be so 100 adjusted as to compensate evenly for the pressure upon the diaphragm and prevent

any undue strain upon the parts during the operation of the machine, and at the same time regulating the amount of pressure.

This machine is intended to be attached directly to the well-pipe or to a high-pressure line of mains, and when the gas is turned off the pressure upon the diaphragm thereby ceases and the diaphragm-stem will drop, seating the valve 32 in its seat 33 below, entirely cutting off the connection between the main and the service-pipe, and the weight will maintain the valve in this position until it is manually raised, the pressure of the gas not being able to accomplish this result, and 15 the device acts perfectly as an automatic cut-off. The descent of the diaphragm-stem during this operation brings the cavity of the cup 14 over the hook 29 of the lever 26, depressing that end of the lever and raising the 20 safety-valve 23 from its seat, thereby opening a free passage to the open air through the outlet-pipe 20 from the chamber above the valve-seat 23, and even if there be any leak whatever through the valve 15 the gas will 25 escape through the pipes 20 and 30 to the open air and will not enter the service-pipe 19, leading to the house, nor accumulate so as to form a pressure sufficient to lift the diaphragm 2, thereby setting the regulator in 30 operation. Again, if anything should happen to the valve 15, such as the wearing away of the valve in its seat or the entrance of a piece of gravel or matter that would prevent the valve from closing tightly, the pressure 35 of the gas would operate to lift the safety-valve, as the latter is set to open at a suitable pressure, so that when the gas-pressure is increased beyond a certain limit it will operate to open the safety-valve and allow the gas to 40 escape to the open air instead of accumulating in the house-pipes, thereby creating a dangerous pressure.

When the weight is lifted by hand to set the mechanism in operation, the engagement 45 of the cup 14 with the hook 29 of the lever 26 is thereby broken and the escape-valve automatically closes. This automatic regulation of the safety-valve is the principal feature of my invention, the other one being the 50 construction of the reducing-valve so as to prevent a jumping or pulsating movement of the latter. The former is the most important, inasmuch as the closing of the regulating-valve invariably and automatically 55 operates to open the safety-valve, so that if there should be any leakage through this valve it would be carried away direct through the open safety-valve to the air. If this arrangement were not provided, the leakage of 60 the gas, however slight at first, would soon cause an accumulation in the house-pipes, which would operate to lift the diaphragm and open the regulating-valve, thereby setting the regulator in operation. By my device it 65 will be seen, therefore, that the admission of the gas to the service-pipe is entirely controlled by the diaphragm, so that whatever be the press-

ure from the well the pressure in the house cannot exceed the amount to which the weight is set, and when the gas is cut off by accident or 70 any other means the gas is entirely shut off from the house-pipe by the automatic action of the device, and the mechanism must be restored to an operative position by hand, while if any gas should leak through the reducing-valve it is carried away through the safety-valve and prevented from accumulating in the house-pipes, thus avoiding a serious source of danger.

What I claim as my invention, and desire 80 to secure by Letters Patent, is the following:

1. In a gas-pressure regulator, a gas-chamber inclosed in a casing, a flexible diaphragm centrally secured therein, a rod connected midway to the diaphragm and above to a 85 lever provided with an adjustable weight and pivoted to the frame and below to a valve seated in a gas-chamber connected to the high-pressure supply, such valve provided with grooves of unequal lengths admitting 90 gas through them successively as the consumption increases, a supply-pipe leading from the gas-chamber, an outlet-pipe also leading from the gas-chamber, connected to a safety-valve whose stem is slotted at the top, 95 and a lever pivoted to the frame, one of its ends entering such slot and the other extending inward and engaging with a cup connected to the diaphragm-stem when the latter is depressed, whereby the lever is tilted and the 100 safety-valve opened, all combined substantially as shown and described.

2. A gas-pressure regulator comprising a gas-chamber inclosed in a suitable casing, a diaphragm secured therein, a stem centrally connected to such diaphragm, its upper end secured to a lever pivoted to the frame, carrying an adjustable weight counterbalancing the pressure beneath the diaphragm, an opening on the under side of the diaphragm-chamber and casing, through which the stem passes, a regulating-valve secured to the lower end of such stem and seated in the walls of an inlet-pipe from the high-pressure supply, a service-pipe leading from the gas-chamber, 115 an outlet-pipe connected to the gas-chamber above the regulating-valve and provided with a safety-valve and a pipe opening into the air, and a lever pivoted to the frame, one end entering a slot in the stem of the safety-valve, the 120 other extending inward and engaging with a cup connected to the diaphragm-stem, whereby the descent of the diaphragm-stem operates to close the valve opening into the high-pressure mains, cutting off the supply and 125 lifting the safety-valve, whereby any leakage passing through the regulating-valve is carried to the open air, substantially as shown and described.

3. A gas-pressure regulator composed of a 130 casing forming a gas-chamber, supply and service pipes leading therefrom, a diaphragm secured within such chamber, and a stem connected to such diaphragm, having a cut-off

valve upon its lower end and within the supply-pipe, such valve closed by the fall of the diaphragm-stem, thereby cutting off the supply from the mains, in combination with a regulating-valve connected to the diaphragm-stem and having its seat on the inlet side, and a safety-valve connected to the gas-chamber and opened by the operation of the diaphragm-stem upon a lever pivoted to the casting, such lever connected to the safety-valve, whereby such valve is opened simultaneously with the closing of the regulating-valve, substantially as shown and described.

4. A gas-pressure regulator composed of a gas-chamber connected with supply and service pipes, a diaphragm secured within such chamber, a stem connected to the diaphragm and above to a pivoted lever having an adjustable weight, a cut-off valve formed on the end of the diaphragm-stem and seated in the base of the outlet-chamber, a regulating-valve connected to the lower end of the diaphragm-stem and seated on the high-pressure side of such wall, and a safety-valve connected to the gas-chamber, such safety-valve and regulat-

ing-valve operated simultaneously by the fall of the diaphragm, substantially as shown and described.

5. In a pressure-regulator, a casing provided with inlet and outlet openings, a diaphragm secured therein, secured centrally to a stem connected below to a valve seated in the high-pressure supply-pipe and above to a lever carrying an adjustable weight, a safety-valve seated in a pipe connected to the regulator on the low-pressure side and adjacent to the outlet, and connections between such valve and the diaphragm-stem for automatically opening the safety-valve when the gas-supply is cut off, whereby any leakage of gas through the cut-off valve is carried to the open air and its accumulation in the house-pipes prevented, substantially as shown and described.

In witness whereof I have hereunto set my hand this 18th day of December, 1890.

JAMES B. KNICKERBOCKER.
